TOBACCO APPLIANCE

Sylvester A. Schramm, Short Hills, N. J.

Application January 22, 1949, Serial No. 72,157

1. Claim. (Cl. 131—257)

1

This invention relates to tobacco appliances and more specifically to devices for preventing fires caused by cigarettes touching bed clothing and the like.

A major fire hazard in homes and hotels is cigarette smoking in bed. Many people like to end the day with a smoke while they are completely relaxed in bed. All too often, however, the smoker falls asleep and the cigarette stub falls from his lips and sets fire to the bed clothing. The present invention, in one of its primary aspects, relates to the prevention of this danger.

It is an object of this invention to provide an appliance which can be attached to a cigarette in such a way that the pleasure of smoking in bed is not diminished and which makes it practically impossible to set fire to the bed clothing.

It is another object of this invention to prevent the lighted end of a cigarette from coming in direct contact with inflammable materials.

These and related objects are attained in accordance with the invention by providing a light-weight device of plastic or other light-weight material which can be attached to a cigarette and be carried thereby while it is being smoked, the device being of such construction that no portion of it is placed in the mouth of the smoker and which has an open-work, globular shield within which the lighted end glows at all times except at the beginning of each smoke and which prevents the end of a partially-smoked cigarette from touching the bed clothing. Moreover, when the lighted end has been smoked to a certain level, it reaches a tube forming the supporting portion of the device and is extinguished. This tube is heavier than the open-work shield so that if the cigarette drops from the mouth (by the relaxation of the mouth muscles when the smoker falls asleep), the cigarette falls on its unlighted end since the tube is near this end.

While the arrangement in accordance with this invention has been described before by way of example in connection with a cigarette, it is obvious that similar devices can be provided for use with cigars. Moreover, it is obvious that the device gives protection against fire to not only bed clothing, but to clothing in general, to carpets, rugs, upholstered furniture, etc.

The invention will be more readily understood by referring to the following description taken in connection with the accompanying drawings forming a part thereof, in which:

Fig. 1 is a side view of a shield in accordance with the invention shown on a cigarette in the smoker's mouth;

2

Fig. 2 is an enlarged view of the shield shown in Fig. 1, the view being taken from the side;

Fig. 3 is a side view of the shield with portions of the support tube thereof being shown in section;

Fig. 4 illustrates the manner in which the shield in accordance with the invention raises the lighted end of the cigarette from the supporting surface; and

Fig. 5 is an enlarged cross-sectional view of a modified support tube for the shield.

Referring more specifically to the drawing, Figs. 1 to 4, inclusive, show, by way of example for purpose of illustration, a shield 10 in accordance with the invention. The shield comprises a support tube 11 and an open-work globular portion 12 attached at one end only to the support tube. The whole device is made of light-weight plastic or other light-weight material and preferably weighs little more than the cigarette 13 from which it is supported.

The support tube 11 may be of smooth cylindrical construction, as shown in Fig. 3, or it may have raised nipples 14 or the like in the inner portion thereof to more closely engage the cigarette, this latter construction being shown in Fig. 5. The support tube weighs more than the globular portion 12 (because of its extreme open-work construction) so that if the cigarette is dropped, the butt end 15 of the cigarette 13 (the end adapted to be inserted in the smoker's mouth) touches the supporting object 17 (such as bed-clothing or carpets, for example) and the lighted end 16 is held up above it, as shown in Fig. 4. The cigarette then burns (with the end 16 within the globe 12) until the lighted end reaches the tube 11 where the glow is extinguished. The open work of the globular portion 12 permits combustion while the lighted end of the cigarette is within its confines.

In order not to diminish the pleasure of smoking, the support tube 11 is not positioned to be placed in the smoker's mouth but is in front of it, as shown in Fig. 1. The cigarette can be easily placed within the support tube 11 and slid therein to the most convenient position. The device can be held easily in the palm of the hand and thereby provides a convenient and restful means of holding the cigarette. Moreover, the device, with a lighted cigarette within, may be placed on a table top or other flat surface without danger of causing damage.

It is contemplated that devices of the character described can be furnished by hotels to their guests since the manufacturing costs are

very low. Hotels have had a large number of bed fires and the furnishing of devices of this kind is a cheap form of insurance.

Obviously, many changes can be made in the embodiment described above without departing from the spirit of the invention, the scope of which is indicated in the appended claim.

What is claimed is:

A shield for a smoking article of the class of cigarettes and the like comprising a support tube adapted to grip the article near the mouth end thereof and having a length only a small fraction of the length of said article, and an open-work globular member attached at one end portion thereof to the support tube and having an opening at the other end portion for the article to pass therethrough, said globular member having a diameter at the largest portion thereof which is at least several times the article diameter and having a length which is shorter than that of said article before use and said support

member having a greater density than said globular member.

SYLVESTER A. SCHRAMM.
